UNITED STATES PATENT OFFICE

2,452,061

THERMIONIC TUBE STRUCTURE

Norman B. Krim, Newton Highlands, Mass., assignor to Raytheon Manufacturing Company, Newton, Mass., a corporation of Delaware

Application January 19, 1946, Serial No. 642,404

6 Claims. (Cl. 250—27.5)

1

This invention relates to thermionic tube structures, and more particularly to the lead-in conductors for certain tube elements.

It is well known that if a thermionic tube used in a voltage amplifier has high grid-plate capacitance, the relatively large variations of plate voltage may induce appreciable variations of grid voltage, and that if the phase relations are correct, this induced grid voltage may add to the impressed alternating voltage in such a manner as to cause the amplifier to oscillate, which is undesirable. In the past, in order to reduce this grid-plate capacitance, a screen grid has been interposed to shield the grid from the plate, and the control-grid terminal has been placed at the top of the tube, instead of on the base. However, in a tube of the "sub-miniature" type it is impracticable to place the control-grid terminal at the top of the tube, and, even though a screen grid is used to shield the elements themselves inside the tube, an objectionable capacitance exists between the grid and plate leads due to the fact that they pass parallel and very close to each other through the glass seal into the tube envelope.

An object of this invention is reduction of the capacitance which exists between the grid and plate leads of a thermionic tube.

Another object is to devise an inexpensive means for reducing the capacitance existing between the grid and plate leads of a thermionic tube of the "sub-miniature" type, which is the type particularly adapted for use in hearing aids or pocket radio receivers.

A further object is to devise a tube structure which is capable of use at very high frequencies.

The foregoing and other objects of the invention will be best understood from the following description of some exemplifications thereof, reference being had to the accompanying drawing, wherein:

Fig. 1 is a longitudinal cross-section through a tube of the invention but with the tube elements shown in elevation;

Fig. 2 is a fragmentary view of a tube, similar to Fig. 1 but showing a modified construction; and

Fig. 3 is a fragmentary side view of the tube taken along line 3—3 of Fig. 1.

Referring to the drawing and more particularly to Fig. 1 thereof, there is shown a thermionic tube of the "sub-miniature" type. The tube electrode assembly, generally indicated at 1, is sealed inside an envelope 2 of some suitable material, such as glass. Upper and lower mica spacers 3

2

and 4, respectively, which engage the inside walls of the envelope at their peripheries, serve as spacing and insulating supports for the elements of the tube. Side support rods 5 and 6 are firmly attached to spacers 3 and 4 by means of clips 7 and in turn serve as grid supports for the wire 8 of the outermost or number three grid, which wire is wound in helical fashion on rods 5 and 6 between the two spacers. Wire 9 of the intermediate or number two grid is similarly wound in helical fashion on similar support rods 10 and 11 which are also attached to the spacers 3 and 4. Wire 12 of the innermost or control or number one grid is wound helically on side support rods 13 and 14, which are attached firmly to spacers 3 and 4 and which extend some distance below the lower spacer 4, as do also support rods 5, 6, 10 and 11.

A pair of flat anode plates 15 are positioned on opposite sides of the flat portions of the grids, each being mounted upon a U-shaped frame 16 made of some suitable material, such as nickel wire. The flat portion of each of these frames engages the top of insulating spacer 3, depending side arms 17 and 18 thereof extending through holes in spacers 3 and 4, below the bottom spacer 4, and having plates 15 welded thereto between spacers 3 and 4. In order to electrically connect and securely fasten in place the two anode plates 15, a double-armed bracket (not shown), which engages the lower side of spacer 4, is welded to the lower ends of each of the side arms 17.

The filament 19 is supported between a conducting spring member 20 at its upper end and a bracket 21 at its lower end, the bracket being fixed to insulating plate 4 by means of rivets 22. The spring member 20 is welded at one end to the upper end of the filamentary cathode 19 and at its other end to side rod 5. The lower end of the filament 19 is welded to bracket 21. A support 23 containing a number of cups for getter material may be conveniently supported on the electrode assembly by being welded to the upper end of side rod 6.

A plurality of lead-in conductors are provided for the electrodes, all of the lead-ins being sealed through a lower flat press 24 formed externally on envelope 2 to provide external electrical connections to the various electrodes. It will be apparent to those skilled in the art that, due to the parallel position and extremely close spacing of the lead-in conductors or wires for the control grid and plate, an objectionable amount of capacitance will exist between these two lead-ins, and the object of this invention is to reduce

this capacitance. To accomplish this result, plate lead-in 25, which inside the envelope is welded to side arm 17 and is therefore electrically connected to plates 15, is surrounded over a portion of the length thereof by a hollow metallic tube 26 which is maintained at ground potential and which, in effect, electrostatically shields lead-in 25 from the other lead-ins. Tube 26 surrounds conductor 25 through the entire length of the flat press 24 and also a substantial distance above and below said press. Control grid lead-in 27, which at its upper end inside the envelope is spot-welded to rod 14 and is therefore electrically connected to control grid 12, is similarly surrounded or shielded by a hollow metallic tube 28, which surrounds lead-in 27 entirely through the length of the press 24 and some little distance above and below the same and which is also grounded. In order to conveniently provide lead-ins 25 and 27 with their respective shields 26 and 28, a short section of coaxial line is used for the plate lead-in 25-26, and another short section of coaxial line for the grid lead-in 27-28. In order to increase the mechanical strength of the sections of coaxial line, so that the outer conductors will not be crushed when the press is produced, a filler 29 of low loss material, for example polystyrene, is provided in each section of coaxial line to entirely fill up the space inside the outer hollow tubes which is not occupied by the inner wires 25 or 27 respectively. In order to provide an airtight seal between the inner and outer conductors of each section of coaxial line, a globule of glass 30 is provided in the inner end of each section of coaxial line and is melted in position to effectively seal the space between the inner and outer conductors of each section. Wire 31 is welded to the intermediate grid support rod 14 to serve as the lead-in conductor for this grid, and this wire, along with the sections of coaxial line 25-26 and 27-28, are sealed through the press in the usual way to provide lead-ins for the electrodes of the tube. Lead 32 is welded at one end to rod 5 and at its other end to outer conductor 26 of coaxial line 25-26 to provide electrical connection to the upper end of the filament. Lead 33 is welded at one end to bracket 21 and is sealed through press 24 to serve as a lead-in to the lower end of the filamentary cathode.

The embodiment of Fig. 2 differs from that of Fig. 1 only in that the grounded shields, or the outer conductors of the coaxial line sections of the control grid and plate lead-ins, are not solid metallic tubes, but are conductors woven of metallic strands into a hollow cylindrical configuration. In order to produce such coaxial line sections, an annulus of glass is molded onto each of the inner conductors 25 and 27, and then a braided metallic covering 34 or 35 is woven on this glass cylindrical base, using a braiding machine. Caps, consisting of metal bands 36 and 37, are fastened to opposite ends of braiding 34 to prevent unraveling of the braiding, while caps 38 and 39 are fastened to opposite ends of braiding 35 for the same purpose. Leads 32 and 33 are welded to caps 37 and 38, respectively, to provide electrical connections between the outer conductors of the coaxial lines and the opposite ends of the filament, as in Fig. 1. Here also, the coaxial sections extend entirely through flat press 24 and a substantial distance above and below the same. When the glass of envelope 2 is heated, preparatory to formation of the flat press

24, the glass of the envelope will fuse or coalesce with the glass which is inside each of the braidings to provide effectively integral, air-tight seals between solid inner conductors 25 and 27, and the press 24. In Fig. 2, then, no glass globules 30 are needed, and the required mechanical strength of the coaxial line sections is provided by the inner cylinders of glass on which the braided outer conductors are woven. In Fig. 2, the same electrical connections are provided as in Fig. 1, and lead-ins 31, 25-34, and 27-35 are all sealed into press 24. In Fig. 2, the grounded braidings 34 and 35 have the same effect as the tubes 26 and 28 of Fig. 1; that is, they effectively shield the grid and plate lead-ins from each other, thereby reducing the capacitance between these two lead-ins.

The outer conductors of the coaxial lines in both embodiments shown should be made of a metal which will seal in a vacuum-tight manner with glass, so that such a seal can be achieved around the peripheries of the outer conductors of the coaxial lines. In Fig. 1, for example, the solid outer tube should be made of a material such as copper or chrome iron, while the outer woven conductor of Fig. 2 should be made of a material such as copper, domet, or tungsten.

Of course, it is to be understood that this invention is not limited to the particular details as described above, as many equivalents will suggest themselves to those skilled in the art. For example, for tubes adapted for use at very high frequencies, in systems using coaxial lines as conductors of high-frequency currents, a tube utilizing this invention can be inserted directly into the coaxial line, utilizing coaxial lines for grid and plate lead-ins in accordance with the teachings of this invention, but placing the two coaxial lead-ins of the invention in opposite ends 40 of the tube. Also, the invention may be used in connection with types of envelopes other than that shown, such as flat press receiving tubes, "acorn" tubes, tubes having a "button" stem, etc. It is also possible to eliminate the strengthening 45 filler in the coaxial line sections. Although the invention has been described with reference to a pentode, it will be obvious that it is equally applicable to a triode or to a tube having any number of elements, as long as it has a control 50 grid and an anode or plate. Various other variations will suggest themselves. It is accordingly desired that the appended claims be given a broad interpretation commensurate with the scope of this invention within the art.

What is claimed is:

1. Means for reducing the total grid-element-to-plate-element capacitance of a thermionic tube in a sealed envelope comprising two metallic shields, one of said shields surrounding a portion 60 of the lead-in wire of one of said elements, the other of said shields surrounding a portion of the lead-in wire of the other of said elements, each of said portions being the part of the respective lead-in wire which passes through the seal into said envelope.
2. A thermionic tube comprising a grid, a cathode on one side of said grid, a plate on the opposite side of said grid, and means for reducing the total grid-plate capacitance of said tube, said 70 means consisting of a pair of metallic shields, one of which surrounds the lead-in conductor for the grid and the other of which surrounds the lead-in conductor for the plate.
3. A thermionic tube structure comprising a 75 sealed envelope, cathode, grid, and plate elements

mounted inside said envelope, and lead-in conductors for each of said elements passing through a sealing portion into said envelope, the lead-in conductors for the grid and plate elements each comprising a section of coaxial line which passes through said portion and is sealed thereinto.

4. Lead-in conductor structure for the grid and plate elements of a thermionic tube in a sealed envelope, which comprises a press element at one end of said envelope and a pair of spaced coaxial lines sealed through said press element into the interior of said envelope, the inner conductor of one line being connected to said grid element and the inner conductor of the other line being connected to said plate element.

5. Lead-in conductor structure for the grid and plate elements of a thermionic tube in a sealed envelope, which comprises a press element at one end of said envelope and a pair of spaced coaxial lines sealed through said press element into the interior of said envelope, each of the coaxial lines consisting of an outer hollow metallic tube, an inner metallic conductor mounted therein, and a filler of low loss material occupying the remainder of the space inside the outer tube, the inner conductor of one line being connected to said grid

element and the inner conductor of the other line being connected to said plate element.

6. Lead-in conductor structure for the grid and plate elements of a thermionic tube in a sealed envelope, which comprises a press element at one end of said envelope and a pair of spaced coaxial lines sealed through said press element into the interior of said envelope, each of the coaxial lines consisting of an outer conductor woven of metallic strands, an inner metallic conductor mounted therein, and a filler of plastic material occupying the remainder of the space inside the outer tube and filling the spaces between said strands, the inner conductor of one line being connected to said grid element and the inner conductor of the other line being connected to said plate element.
